SNAP ACTION SWITCH

William F. Auer, Cicero, Ill., assignor to
Raymond T. Moloney, Chicago, Ill.

Application November 13, 1950, Serial No. 195,337

3 Claims. (Cl. 200—67)

1

The present disclosures pertain to improvements in a snap action switch relating principally to a new type of over-center or snap-action spring, characterized mainly in the provision of a bow spring having a bifurcated or forked end with offset rocker formations to seat in marginal slots in an over-passing operator spring.

The important objects of the improvements are the provision of a simple over-center snap-action spring having a three-point suspension or engagement with an associated moving contact blade and its cooperating over-passing operator blade, whereby the bow spring is easily and securely seated and has an enlarged and stabilized two-point rocking seat on the operator blade with the third point of suspension on the movable blade situated in triangular array with the other two points.

The foregoing objects and other aspects of novelty and utility inherent in the improvements will become apparent as the following description proceeds in view of the annexed drawing, in which:

Fig. 1 is a top plan view of the improved switch;
Fig. 2 is a side elevation of the same;

Fig. 3 is a magnified vertical section of the snap-action part of the switch;

Fig. 4 is a sectional view like that of Fig. 3, but showing the snap mechanism actuated;

Fig. 5 is a perspective detail of the new bow spring;

Fig. 6 is a perspective fragment of the over-passing operator blade for the bow spring.

The type of switch to which the improvements are applied for illustration herein is commonly known as a stack switch, which, as seen in Fig. 2, consists of a stack of insulating wafers generally indicated at 10, between which are clamped (by action of bolts and nuts 11) a pair of relatively rigid flanking or outer contact blades 12 and 13.

Mounted in the stack to flex between said flanking contacts 12 and 13, is a thin spring contact blade 14, having at its outer or free end a small tongue 15 (Fig. 3).

An over-center bow spring 16, such as shown in Fig. 5, made from thin flat metal stock or ribbon, is provided at one of its ends with a small die-punched slot 16A interfitting with tongue 15 to provide one of the endwise rocking mounts or three-point assemblies of the spring with the flexible or movable contact blade.

At its opposite or remaining end, the bow spring is somewhat wider than the adjoining spring stock, and has punched in the widened part a cut-out, for instance, in the form of

2

(Fig. 5) an arcuate transverse slot 16B flanked by opposite side wings 16C which afford an expanse of metal stock to provide the opposite offsets or lugs 16D.

5 The wings and offsets 16C—16D constitute a pair of rockers at the outer or remote side of the bow spring.

The assembly is completed by provision of an operator blade 17, also flexible, and as seen in Fig. 6, having a central cut-out 17A large enough to permit up and down flexing of the movable contact blade 14 therein, and conversely permitting relative movement of the operator blade up and down past the contact blade, by reason of which action the operator blade is designated herein as an "over-passing" operator blade.

Near the outer or free end, remote from the free end of the flexible contact blade 14, the operator blade 17 is provided with a pair of opposite, 20 edgewise, fulcrum notches 17B dimensioned to admit the rocker formations or offsets 16C—16D.

The outermost edges (nearest the free end of the operator blade) of the rocker notches are preferably straight and perpendicular to the long 25 axis of the blade, so as to afford a straight knife-edge or fulcrum for rocking motion of the outer end of the bow spring relative to the operator spring when the latter is moved up and down in operating the switch; and the location of said notches is spaced from the free end of the movable switch blade (and hence the tongue 15) sufficiently to place the bow spring under some compression in assembly (as in Figs. 2 and 3).

30 Preferably, also, the operator blade is biased so as to cause the snap mechanism to assume the normal position shown in Figs. 2 and 3 with the bow spring 16 urging the movable contact downwardly against the lower stationary contact 12.

When a downward pressure is applied to the 40 free end of the operator blade 17 so as to displace the latter from the condition of Fig. 3 toward the operated condition of Fig. 4, the operator blade is seen to over-pass the contact blade 14, and the bow spring 16 will pass reversely into an over-center relation to its mounting at 15A—16A with the movable contact blade, and abruptly reverse its thrust to urge the movable contact 14 upwardly into the snap-operated condition shown in Fig. 4, the opposite end parts 16C—16D of the bow rocking easily in a two-point seating in notches 17B in such action.

45 Actually, the bow spring has a three-point suspension in which the points of suspension are in a triangular array, one point on tongue 15 and the other two in notches 17B. When the operating

pressure is relieved from the operator blade, the further compression in the bow spring 16 and normal bias of the operator blade 17 will abruptly restore the parts to the normal condition of Fig. 3, in a snap-action which is the reverse of the operating action just described.

The new construction disclosed has the advantages of being very economical to manufacture, and very simple to assemble by reason of the fact that the bow springs are fully formed as they come from the dies and no adjustments are required in mounting them in operative position. Also the snap-action is satisfactory in both fine and coarse throws of the movable blade, as where contacts 12 and 13 are spaced relatively far apart or close together.

The improved construction requires no intermediate moving or connecting parts between either the bow and the movable contact, or the bow and the operator blade; and the two-point rocker mounting as at 16C-16D-17B on opposite sides of the operator blade affords a greatly enlarged area of rocking support for the bow spring in the region where its displacement is greatest, while at the same time the bow is very secure against accidental dislodgement, it being noted in this connection, also, that the curved or forked cut-out 16B prevents any upward movement of the bow spring which might disengage the latter from its rocking seat.

Once assembled, the bow spring is practically locked in position in its three-point suspension.

The novel construction is also advantageous in that it is equally effective with very short contacts 12-13-14, or the longer blades frequently employed.

I claim:

1. In a snap switch of the type having a movable contact blade cooperable with an over-passing operator blade, improvements comprising, to wit: over-center snap-action spring means in the form of a bow of flat spring metal, one end of said bow being enlarged and having a transverse cut-out with its opposite side portions terminating in offsets constituting a pair of rockers, said operator blade having a pair of transversely-aligned edgewise fulcrum notches each receiving and seating one of said rockers with said cut-out underlying the transverse region of the blade between said notches, the opposite end of said bow being supportably engaged for slight movement with an end portion of said movable blade.
2. In a snap-action switch of the known type which includes a flexible contact blade with an over-passing operator blade and a snap-acting

over-center spring interposed operatively between a free end portion of the contact blade and a confronting part of the over-passing blade, improvements comprising, to wit: improved over-center spring means including a bow spring having one end forked with a cut-out portion to define two prongs, said prongs being offset to afford a pair of laterally spaced rockers flanking said cut-out portion, said over-passing blade having a pair of laterally-spaced notches in which said rockers are respectively received, the opposite end region of said spring being supportably engaged with said free end portion of the contact blade, so as to be compressible by movement of the operator blade relative to the contact blade, said cut-out portion being of a depth to clear the operator blade in operational movements of the latter.

3. In a snap switch of the known variety which includes an elongated contact blade fixed at one end and free to be flexed from its opposite free end, snap-action means comprising: an elongated operator blade also fixed at one end with said contact blade and spring-biased to a normal position and also having a central cut-out which can pass over said free end of the contact blade in flexures of the operator blade, and a bowed, flat-stock over-center spring having tongue and slot engagement at one of its ends with said free end of said contact blade, and having at its opposite end forked with opposite rocker offsets rockably seated in edgewise notches in the operator blade adjacent the free end region of the latter, said bow spring being normally under compression and acting in over-center snap-action with said movable contact responsive to operative displacements of said operator blade relative to said normal position to throw the movable contact back and forth between normal and operated positions, and stationary limiting means, including at least one stationary contact, flanking said movable blade to determine said positions.

WILLIAM F. AUER.
